UNITED STATES PATENT OFFICE

164,306

TOILET ARTICLE TRAY

August S. Korbus, Detroit, Mich.

Application April 19, 1951, Serial No. 14,888

Term of patent 3½ years

(Cl. D4—3)

To all whom it may concern:

Be it known that I, August S. Korbus, a citizen of the United States, residing at Detroit, in the county of Wayne and State of Michigan, have invented a new, original, and ornamental Design for Toilet Article Tray, of which the following is a specification, reference being had to the accompanying drawings, forming part thereof.

I claim:

The ornamental design for a toilet article tray, as shown.

AUGUST S. KORBUS.
